UNITED STATES PATENT OFFICE.

ZEMACH AUERBACH, OF NEW YORK, N. Y.

FOLDABLE CARD.

Application filed April 6, 1922. Serial No. 550,233.

To all whom it may concern:

Be it known that I, ZEMACH AUERBACH, a citizen of the United States, and resident of New York city, borough of Manhattan, 5 in the county of New York and State of New York, have invented certain new and useful Improvements in Foldable Cards, of which the following is a specification.

This application is a continuation in part 10 of my application, Serial No. 523844, filed December 21, 1921, Patent No. 1,414,721, and has particular reference to improvements in cards or sheets of paper to be filed and upon which names, appointments, accounts and 15 other memoranda may be kept for reference.

The object of my invention is to provide a foldable card that may be folded into a relatively small compass for filing and extended into a relatively elongated condition 20 for use and reference, to provide for marking a considerable number of items thereon.

In carrying out my invention I provide a foldable card comprising a piece of material having lateral projections at its free ends 25 and adapted to be folded between said free ends, said material being provided with other lateral projections adjacent to such fold, whereby the webs of the card, when it is folded, may be hung upon spaced supports. 30

My invention also comprises novel details of improvement that will be more fully hereinafter set forth, and then pointed out in the claims.

Reference is to be had to the accompanying drawings forming part hereof wherein,

Figure 1 is a perspective view of my improved card, folded for filing;

Fig. 2 is an edge view thereof;

Fig. 3 illustrates the card opened out for use;

Figs. 4 and 5 illustrate the cards having side flaps;

Fig. 6 illustrates the card having a replaceable designating card;

Fig. 7 is an edge view of Fig. 6; and

Fig. 8 is an enlarged sectional detail of Fig. 6.

Similar numerals of reference indicate 50 corresponding parts in the several views.

The foldable card is indicated at 5, which may be of a single thickness of material adapted to have memoranda written or printed thereon. The cards are foldable to 55 extend their length from the normal condition for filing as indicated in Figs. 1, 2, 6,

7, 8, and 11. In the example shown the cards may in the form of strips of paper of suitable length folded at 5^b, which is approximately midway of the length of the 60 card, to form double ply of thickness to bring their free ends adjacent and provided with lateral projections 5^c at such folded portion 5^b. When the card is folded at 5^b the projections 5^c also will be folded as indicated in Figs. 1 and 6. At the opposite or free ends of the cards the same are provided with lateral projections 5^a and said cards may be again folded at 5^a substantially midway of the first fold and the free ends to 70 reduce the length of the cards and provide extended surfaces on both sides thereof to be written or printed upon. When the cards are folded, as in Figs. 1, 2, 6 and 7, the corresponding projections 5^a and 5^c will be located close together or in register so that the folded cards may be hung by such projections upon suitable spaced supports. The cards may be used and supported in any suitable racks, such as set forth in my afore- 75 said application.

While a name or designation may be written or printed upon the upper edge portion of card 5, as shown in Fig. 1, the upper edge portion may be folded over as indicated at 80 10 in Figs. 6, 7, and 8, the lower edge thereof being stuck to the card for a distance to provide a pocket or guideway 11^a to receive a detachable card 11, having a name or designation thereon that will appear 85 through an opening 10^a in the folded-over portion 10, so that such cards 11 may be inserted and replaced as may be required.

While in Figs. 1, 2, 3, 6, 7, 8, the cards are 90 illustrated as having a single body portion on which memoranda or the like may be written or printed, the cards also may be provided with lateral wings or flaps 6, adapted to be folded, as on the longitudinal lines 7, over the main adjacent portions of 100 the cards. The wings 6 may be on one or both sides of the cards, as indicated in Figs. 4 and 5. The construction described enables the wings 6 to be folded within or along the main faces of the cards and then to be folded within the cards when the latter are folded along the lines 5^b and 5^c to provide the folded cards in compact form in a relatively small compass compared to the dimensions of the cards when opened out fully. 110 The wings 6 will be retained in their folded condition by reason of the double folding

of the cards at 5^b, 5^d. By preference the wings 6 are separate, as along the dividing lines 6^a, so as to fold more snugly corresponding to the fold lines 5^e.

5 While I have illustrated the projections 5^a and 5^c in Figs. 1 to 8 as formed integrally with the material of the cards, such projections may be otherwise provided on the cards.

10 My improved card may be used in various relations, such as for keeping appointments with a person's name entered thereon and for entering on the card memoranda regarding an interview and other data, as well as 15 for enclosing papers with the card in the nature of a folder. The space occupied by the card is relatively small compared to the extent of card surface when the latter is opened out, so that the cards may be hung 20 by their lateral projections in a rack, such as shown in my aforesaid application, in a convenient and compact manner.

Having now described my invention, what I claim is:—

25 1. A card of the class described, comprising a piece of flexible material having lateral projections at its ends, the material being folded between its ends and provided with lateral projections adjacent to such fold.

30 2. A card of the class described, comprising a piece of flexible material having lateral projections at its ends, the material being folded between its ends and provided 35 with lateral projections adjacent to such fold, said folded material having a fold between the first-named fold and the free

edges of the material, the projections at the ends of the material and the projections adjacent to the first named fold being adjacent to one another at opposite sides of the folded card.

3. A card of the class described comprising a piece of flexible material having lateral projections at its ends and having lateral projections midway between its ends, said material having a fold at said midway portion and the projections thereat being folded, such material having a fold between the midway portion and its ends and all of the corresponding projections on opposite sides of the card being adjacent.

4. A card of the class described, comprising a piece of flexible material having lateral projections at its ends, the material being folded between its ends and provided with lateral projections adjacent to such fold, said material having foldable wings at its sides between the first named and second named projections.

5. A card of the class described, comprising a piece of flexible material having lateral projections at its ends, the material being folded between its ends and provided with lateral projections adjacent to such fold, said material having a pocket along one end edge portion provided with an opening, and a detachable card insertable in said pocket to appear through said opening.

Signed at New York city, in the county 70 of New York, and State of New York, this 4th day of April, A. D. 1922.

ZEMACH AUERBACH.
